US00D697141S

(12) **United States Design Patent**
Sugino et al.

(10) **Patent No.:** **US D697,141 S**
(45) **Date of Patent:** **** Jan. 7, 2014**

(54) **HOUSING COMPONENT FOR ELECTRONIC COMPUTER**

(71) Applicant: **Nintendo Co., Ltd.**, Kyoto (JP)

(72) Inventors: **Kenichi Sugino**, Kyoto (JP); **Yui Ehara**, Kyoto (JP); **Takaki Fujino**, Kyoto (JP); **Junichiro Miyatake**, Kyoto (JP); **Tetsuya Akama**, Kyoto (JP); **Munetaka Nishikawa**, Kyoto (JP)

(73) Assignee: **Nintendo Co., Ltd.**, Kyoto (JP)

(**) Term: **14 Years**

(21) Appl. No.: **29/439,977**

(22) Filed: **Dec. 18, 2012**

(30) **Foreign Application Priority Data**

Jun. 18, 2012 (JP) 2012-014503
(51) **LOC (10) Cl.** **21-01**
(52) **U.S. Cl.** ..... **USPC** **D21/333; D14/345**
(58) **Field of Classification Search**
USPC ..... D21/324, 329, 330, 333, 332; D14/496, D14/125, 345, 203.1, 314, 315, 356, 365; 273/148 B; 463/1, 2, 29-36, 45, 47; 345/156, 173, 867, 903; 361/679, 681, 361/672, 500

(57) **CLAIM**

The ornamental design for a housing component for electronic computer, as shown and described.

DESCRIPTION

FIG. 1 is front, right and bottom perspective view of a housing component for electronic computer showing our new design; FIG. 2 is rear, left and top perspective view thereof; FIG. 3 is a front view thereof; FIG. 4 is a rear view thereof; FIG. 5 is a top plan view thereof; FIG. 6 is a bottom plan view thereof; FIG. 7 is a left side view thereof; and, FIG. 8 is a right side view thereof.
